UNITED STATES PATENT OFFICE.

ULRICH HAGMANN, OF NEW YORK, N. Y., ASSIGNOR TO SEBRING POTTERY CO., OF SEBRING, OHIO, A CORPORATION OF OHIO.

DESIGN FOR A PLATE OR SIMILAR ARTICLE.

Application filed August 22, 1925. Serial No. 14,563. Term of patent 3½ years.

To all whom it may concern:

Be it known that I, ULRICH HAGMANN, a citizen of Switzerland, and resident of St. George, in the borough and county of Richmond, city and State of New York, have invented a new, original, and ornamental Design for a Plate or Similar Article, of which the following is a specification, reference being had to the accompanying drawing, forming part thereof, which drawing is a face view of a plate or similar article illustrating my new design, the dotted lines indicating that the ornament shown at the upper part of the drawing is to be repeated around the plate.

I claim:

The ornamental design for a plate or similar article, as shown.

ULRICH HAGMANN.
